UNITED STATES PATENT OFFICE

148,284

DESIGN FOR A CLOCK

William A. Clarke, Jr., New Lexington, Ohio

Application June 26, 1947, Serial No. 139,928

Term of patent 14 years

(Cl. D42—7)

To all whom it may concern:

Be it known that I, William A. Clarke, Jr., a citizen of the United States, residing at New Lexington, in the county of Perry and State of Ohio, have invented a new, original, and ornamental Design for a Clock, of which the following is a specification, reference being had to the accompanying drawing, forming part thereof.

The figure is a perspective view of a clock, showing my new design.

The appearance of the two sides of the clock not shown is substantially the same as that illustrated.

I claim:

The ornamental design for a clock, as shown and described.

WILLIAM A. CLARKE, JR.
